UNITED STATES PATENT OFFICE.

GILBERT Y. LOWE, OF WASHINGTON, GEORGIA.

DESIGN FOR AN AXLE-SHIELD.

SPECIFICATION forming part of Design No. 33,649, dated December 4, 1900.

Application filed November 10, 1900. Serial No. 36,138. Term of patent 14 years.

To all whom it may concern:

Be it known that I, GILBERT Y. LOWE, a citizen of the United States, and a resident of Washington, in the county of Wilkes and State of Georgia, have invented and produced a new and original Design for an Axle-Shield, of which the following is a full, clear, and exact specification.

Reference is to be had to the accompanying drawings, forming a part of this specification, in which similar characters of reference indicate corresponding parts in all the views.

Figure 1 is a perspective view of an axle-shield embodying my design. Fig. 2 is a longitudinal section thereof, and Fig. 3 is a rear elevation.

The design in its entirety comprises a transversely-curved front portion *a* and a correspondingly-curved rear portion *b*, the rear portion *b*, however, being reduced in size and being curved in an arc out of conformity with that of the part *a*.

The design further comprises a sloping intermediate part *c*, establishing contiguity between the parts *a* and *b*, and the rear extremity of the part *b* presents at its lower sides inwardly-projected lips *b'*.

The leading feature of the design consists in the transversely-curved longitudinally-aligned front and rear parts *a* and *b*, the latter presenting the inwardly-projecting lip-like elements *b'*.

Having described my invention, what I claim as new, and desire to secure by Letters Patent, is—

The design for an axle-shield, as herein shown and described.

In testimony whereof I have signed my name to this specification in the presence of two subscribing witnesses.

GILBERT Y. LOWE.
